FIG. 1.

FIG. 3.

FIG. 2.

YOSHIMITSU KONO,

INVENTOR.

BY *Otto D. Ringer*,

HIS ATTORNEY.

the passage as short as possible, any tilting in any direction will but slightly affect the distance between post and passage at the point of contact with respect to the point of injection.

The post may therefore, quite properly, be called the primary means for establishing contact and location, such as on the skin of a patient of a doctor.

It should furthermore be taken into consideration that the passage has been shown as of rather wide and large size, and the material of the tube has been shown proportionally thick, being shown in Fig. 3 with cross-hatching in cross-section, or rather longitudinal section as far as the axis of the tube is concerned, the thickness of the tube being really only for the sake of clearness of the section-lines, the whole showing of thickness or size being just for purposes of clear detailing in the illustration, though a needle, or instrument of the type to be used with this device may in itself be very slender and thin, and only requires a small passage; the tube would only have to be of thin material, and the tube would be preferably rather snugly fitting.

From all this, it should be understood that the tube may be of such a small proportion as not to materially obstruct any view, so that the point of injection may easily be observable while the tube is practically directly over the point of injection, or the point of injection practically directly under the tube-end.

Having provided the double-U-shaped form for the main frame, makes it possible to have the tube-end under convenient observation through the comparatively large opening in the main frame at all times, which is one of the strong features of this invention.

To this feature is added that an instrument can be guided by the tube close to the surface while the tube and main frame is firmly pressed to, and so disposed on, a tauntly stretched surface, which any person skilled in the art will appreciate as of great advantage for the purpose intended and specified herewith.

Contacting and positioning may thus quite positively be predetermined in definite locations, such as desired places near the spine of a person.

The locating post may thus also be used for feeling and locating a proper position at which an injection is to be made.

Once having thus predetermined a desired position and location for an injection, such a position and location is easily retained by means of the post while the main frame is then moved to a desired inclination to bring the passage into the proper direction for the intended injection.

At this juncture, or stage of operation, the post serves as a temporary support while the four legs are adjusted for the more permanent support of the main frame preparatory to the actual injection operation.

Naturally, an operator will choose one leg after the other in the order found most convenient and in which they will help to maintain the adjusted position of the main frame most conveniently.

Using the locating post thus as a primary means for establishing contact and location with the surface upon which the device is to be used, the post facilitates definitely a placing of the device with regard to the point at which an injection is to be made, preparatory to adjusting and setting the legs 8-8'.

Using the locating post as a primary means for

establishing contact with the surface upon which the device is to be used, the post also helps to retain the device in the adjusted position while the downwardly and outwardly spreading legs are used to stretch the surface material in all directions laterally about the guiding tube and its passage.

In other words, and in short terminology, the post 4 is used as a preliminary support and guide preparatory to the proper placement of the tube with respect to the proposed site and direction of operation, and may also be used to steady the device with the tube in proper operative alignment preparatory to, and until, proper adjustment of the legs can be brought about.

It should be understood that the post may be firmly pressed into the surface and into the flesh to such an extent as to assure a positive retaining of the main frame in the desired position, while the skin and flesh around the post and tube will yield sufficiently to allow a desired stretching of the skin. Such a stretching and drawing can be accomplished from the moment that the padded ends of the legs make contact with the surface of the skin, and the drawing and stretching may be continued as long as the skin and flesh yield, to assure a suitably taut surface for the injection.

From the above description and from the illustration, it should be clear that the downwardly and outwardly spreading legs will assure exactly such a result, since the contacting means 9-9' of the legs 8-8' separate more and more as the legs are pushed outwardly further and further.

After the device has been adjusted so as to form a firmly established base, any co-operating instrument, outlined at 12 in Fig. 3, is simply inserted into and passed through the passage 2 of the tubular member 1.

In cases where it is desirable, the device may readily be removed while the instrument is still in operating position, since the device may be opened as indicated in dotted lines in Fig. 1.

For injection along a spinal column, this device is of particular aid, since the locating post can be used for finding the open spaces of the spine, and the legs can be adjusted to bring the guiding tubular member to the desired angle for a proper injection into the desired space with regard to the column.

The stretching of the skin by means of the legs furthermore facilitates the injection of any instrument in such a manner as to reduce, if not make impossible, any bending of the inserted instrument, as also any slipping of the operator's hand on the surface of the skin, so that misplacements of injections may practically be prevented.

Having thus described my invention, I claim:

1. In a device of the class described, a frame having hingedly connected portions embodying a guiding tubular member, a locating means on the frame in operative relation to the tubular member for a preliminary contact with the surface upon which the device is to be used, and supporting legs mounted on the frame in downwardly and outwardly inclined positions with their contacting ends spreading about the end of the tubular member.

2. In a device of the class described, a frame having hingedly connected portions embodying a guiding tube split longitudinally with the center of the tube spaced from the center of the hinge, a locating means with an axis concentric with the axis of the hinge and in cooperative re-

lation to the tube for preliminary contact with the surface upon which the device is to be used, supporting legs mounted slidably in the frame with their supporting contacting ends spreading about the tube end, and means for adjustably holding the legs in the frame.

3. In a device of the class described, a frame embodying a guiding tube extending downwardly

from the frame, a locating means forming a support for the frame in operative relation to the tube, supporting legs slidably mounted in the frame at angles to spread about the tube-end, gripping contacting means at the ends of the legs, and means for adjustably holding the legs in the frame.

YOSHIMITSU KONO.
